EDUCATIONAL TOY

Vernon G. Eisel, New York, N. Y.

Application April 19, 1944, Serial No. 531,803

10 Claims. (Cl. 35—1)

It is known that children from about fourteen months to five years are interested in lacing and unlacing shoes or other objects.

Lacing is a comparatively complicated skill. It requires repeatedly choosing an eyelet to receive the lace, threading the end of the lace into the eyelet, pushing the lace into one side of the eyelet and pulling the lace through on the other side, after which comes the equally complex skill of choosing the eyelets to be used in succession in order to make the desired lacing pattern.

Unlacing is a simpler exercise, as it requires only pulling. Children begin being interested in unlacing at least as early as fourteen months. They like to practice unlacing over and over until they understand it. Their interest in lacing begins later.

The object in the present invention is to provide a device in which, after the young child has unlaced the lacings, the mother, teacher or child may readily restore the device to its laced condition without actually lacing it up again.

Other objects will appear in the following specification and drawings, in which:

Figure 1 is a plan view partly broken away, of a device made in accordance with the present invention;

Figure 2 is a cross section on the line 2—2 of Figure 1, looking in the direction of the arrow;

Figure 3 is a perspective view of an element of the device shown in Figure 1 and Figure 2 or in Figure 5.

Figure 4 is a plan view of the element shown in Figure 3 showing a different lacing and a modification in perforations;

Figure 5 is a sectional view of a modification;

Figure 6 is a plan view of a further modification;

Figure 7 is a longitudinal section of Fig. 6 on the line 7—7, showing the device unlaced.

The invention comprises a frame 10 and a panel 11 which is adapted to receive laces 12 and which is partially or wholly removable from the frame.

In the embodiment of the invention shown in Figures 1 to 4 inclusive, the frame 10 is shown as having an opening at one end 13 for removal of the panel 11. If desired the open end of the frame may be notched as at 14 to make it easier to grasp the panel. As shown particularly in Fig. 2, the frame is open on both faces, so that both faces 15 and 16 of the panel are accessible.

The sides 17 and the closed end 18 of the frame are grooved at 19 to receive the panel. If desired a reduced tongue 20 may be provided on the sides and on one end of the panel, to co-

operate with the groove 19. Near the other end the panel may be provided with a thumb hold 21 to aid in withdrawing the panel from the frame.

Along each side of the panel is a row of slots 22 for receiving the laces as shown particularly in Figs. 1 and 3. When the panel is assembled in the frame, the edges of each slot 22 together with the cooperating edge 23 of the frame, form an eyelet for the lace 12. The slots 22 may be of any desired depth. Each slot on one side is preferably directly opposite a corresponding slot on the other side. That is to say, corresponding slots are at the ends of an imaginary line drawn across the panel perpendicular to its sides. In the figures the slots are shown spaced along the side equally from each other, but other groupings of the slots may be used.

If desired pairs of additional eyelets 24 may be provided to allow for different patterns of lacing.

As illustrated in Figs. 1 to 4 these eyelets are spaced inwardly from the edges of the panel beyond the inner ends of the slots 22 and are staggered with the slots 22. Means may be provided for securing the laces to the panel such as the holes 25, through which the laces may be tied to hold them in the desired position for lacing and to prevent their being removed from the panel and lost. As illustrated in Fig. 4, at the other end of the panel there may, if desired, be provided another pair of holes 25x, to take the place of the final pair of slots 22 through which the laces may be threaded at the completion of the lacing just before tying a final knot or bow, but these holes are optional. As shown in Figure 4, the holes 25x are aligned with the inner ends of the slots 22.

The lace 12 preferably is arranged so as to have two substantially equal segments 26, 27 which may be provided by securing the lace 12 at its center to the panel. This may be accomplished by inserting the lace through the holes 25 and tying it. If desired the two segments may be of different colors. In the drawings one segment 26 is shown as red and the other as white.

In using the device, the procedure is as follows:

As stated above, the interest of the very young child is in unlacing, therefore, the device preferably is handed to him with the panel in place in the frame, and with the lace laced up in a conventional manner and having its free ends tied in a bow. When thus handed to the child, the laces may be laced either in the eyelets formed by slots 22 as shown in Figs. 1, 2 and 3 or in the eyelets 24 as shown in Fig. 4, or into

any desired combination of the two sets of eyelets.

The child by pulling will untie the bow and unlace the lacings. He will then want his teacher or parent to lace the device again, so that he can repeat the unlacing operation. My invention results in a great saving of time by the teacher. Instead of going through the laborious task of lacing the toy by threading the tips of the laces through each eyelet, the teacher grasps the thumb hold 21 and slides the panel out of the frame. Then she quickly winds the lace around the panel into the slots and ties a bow, slides the panel back into the frame and the toy is ready for the child to unlace again. For the lacing pattern illustrated in Figs. 1 and 3, one segment for example, 27 is wound spirally around the panel being received first in a slot on one edge of the panel and then in the next succeeding slot on the other edge of the panel with the results that alternate slots on each edge are unoccupied, the unoccupied slots being staggered. Then the other segment 26 of the lace is similarly wound, but in the opposite direction into the slots which were first left unoccupied. If a different lacing pattern is desired the winding can be suitably varied.

Later, when the child is old enough to learn lacing, he can use the device in a number of different ways.

He can learn to lace using both the eyelets 22 formed by the frame and the slots and the eyelets 24, or he can learn to lace selectively, using only the eyelets 22 or only the eyelets 24.

In using the device illustrated in Figures 1 and 2 the child has access to both faces 15 and 16 of the panel, as the frame is open on both faces. Thus in unlacing or in lacing the child can turn the frame first to one face to see and touch the laces and eyelets on that face, and then to the opposite face as he works from the opposite face.

Figure 5 shows a modified form of the device in which the frame comprises a box 28 of which the panel 11 forms the top. Thus the frame is closed at one face 16 of the panel in this embodiment.

Like the frame 10, the box 28 is grooved at 19 along the inside of an end 29 and of both sides 30 near the top edge thereof, so that the panel 11 can be slid out of the box like frame 28, in order that the teacher can re-wind the laces, after they have been unlaced by the child.

If desired the box may be made so that not only the top 11, but also one or both ends 29 and 31 may be removed, so that the child's hands may have access to both faces of the panel. As shown in Fig. 5 each end of each side 30 is grooved at 32 to receive the end piece 29 or the end piece 31 of the box. One end 31 is preferably made shorter than the other so that when it is inserted in the box, as shown in Fig. 5, its top will be lower than the groove 19, in order not to interfere with grasping the panel 11 and removing it from the box-like frame 28.

The box may be of any desired shape. In the preferred form the grooves 32 slant diagonally from about the corner of the top edge 33 of side 30 downwardly and inwardly to the bottom edge 34, with the result that ends 29 and 31 slant inwardly from top to bottom, thus making it easy for the child to hold the box. The slanting ends in effect constitute handles by which the box may be lifted.

In using the device shown in Fig. 5, the child when learning to unlace, preferably uses the box

with not only the panel 11, but also the ends 29 and 31 fully inserted in their respective grooves. In learning to unlace, he needs access to only one side of the panel because all he needs to do is to pull the laces toward him. His concentration is aided by the fact that only on one face of this closed-frame does he find the laces.

However, when he has mastered the movement of pulling toward himself, the ends 29 and 31 may be removed if desired, so that he will have access to both faces of the panel with his hands, although he can see only one face. In this stage he can learn to unlace by either pulling toward himself or pulling away from himself.

Later when the child is learning to lace, and must use alternate pulling and pushing movements which lacing requires, the needs to have access to both sides of the object containing the laces through which he is to lace. In the embodiment of Figure 5, therefore, for the lacing exercise, he can use the frame 28 with the ends 29 and 31 removed, so that he can reach under the panel to push or to draw the lace through either the eyelets 24 or through the eyelets 22 formed by the cooperation of the frame 28 and the edges of slots 22 of the panel. Alternatively, if while lacing the child needs to have access to both sides of the panel not only with his hands but also with his eyes, he can remove the panel from the frame and use the eyelets 24 for the lacing.

In Fig. 6 is illustrated a device similar to the device shown in Figure 1 except that the panel 110, instead of being wholly removable from the frame 100 is only partially removable therefrom, the panel being secured to the frame 100 by any suitable means. In this figure the panel is hinged to the frame by means of a pivot 35, but it is understood that any suitable connection may be used.

At the other end, frame 100 is provided with a stop 36 to serve as a seat for the panel and to prevent it swinging beyond the frame 100. The panel and frame are provided with any suitable cooperating latch means such as a pin 37 and cup 38 for holding the panel and frame assembled with each other while the child is lacing or unlacing the device. A spring 39 tends to extend the pin into engagement with the cup, permitting partial separation of the panel from the frame in order that the parent, teacher or child may wind the laces up again.

In this embodiment each eyelet 220 for receiving the laces is formed by the edge of a semi-circular slot 221 in the side of panel 110 and a complementary semi-circular slot 222 in the cooperating frame 100.

In the frame 100 are provided supplemental pairs of eyelets 40 and 41 which may be used in the lacing if desired.

It is not intended to limit the invention to the embodiments illustrated and described. Other modifications within the scope of the invention will occur to those skilled in the art.

I claim:

1. A lacing toy comprising a frame and cooperating means having slots extending inwardly from its edges, whereby when the means is framed the slots form parts of eyelets for laces, said means being at least partially removable from said frame.

2. A lacing toy comprising a frame and cooperating removable means having laces, said means having slots extending inwardly from its

edges, whereby when the means is framed the slots and frame form eyelets for said laces.

3. A lacing toy comprising a frame, a panel at least partially removable from said frame and having slots extending inwardly from its edges whereby when the frame and the panel are assembled the edges of the panel surrounding the slots and adjoining walls of the frame constitute eyelets for lacing and whereby when the panel is removed from the frame laces may be placed in laced position by winding.

4. A lacing toy comprising a frame closed on one face and cooperating means having slots extending inwardly from its edges, whereby when the means is framed the slots form parts of eyelets for laces, said means being at least partially removable from said frame.

5. A lacing toy comprising a frame closed on one face and cooperating means having slots extending inwardly from its edges, whereby when the means is framed the slots and frame form eyelets for laces, said means being at least partially removable from said frame, said frame having removable ends whereby access may be had to both faces of said panel.

6. A lacing toy comprising a frame and cooperating means having slots extending inwardly from its edges, whereby when the means is framed the slots and frame form eyelets for laces, said means being at least partially removable from

10 said frame said frame comprising a box and said frame comprising the top of said box.

5 7. A lacing toy comprising a frame and cooperating means having slots extending inwardly from its edges, whereby when the means is framed the slots and frame form eyelets for laces, said means being at least partially removable from said frame said frame comprising a box and said frame comprising the top thereof, said box having sloping removable ends, whereby access may be had to both faces of said top.

15 8. A lacing toy comprising a frame element and an element at least partially removable therefrom, cooperating edges of said elements forming eyelets for laces.

9. A lacing toy with selective eyelets comprising a frame element and an element at least partially removable therefrom, cooperating edges of said elements forming at least some of the eyelets for laces.

20 10. A lacing toy comprising a frame and cooperating means having slots extending inwardly from its edges, whereby when the means is framed the slots and frame form eyelets for laces, said means being at least partially removable from said frame, and means to prevent the accidental removal of the first named means from the frame during use.

VERNON G. EISEL.
